UNITED STATES PATENT OFFICE.

GUY H. PROCTOR, OF SOMERVILLE, MASSACHUSETTS, ASSIGNOR TO NEW ENGLAND ELECTRIC MANUFACTURING COMPANY, OF BOSTON, MASSACHUSETTS, A CORPORATION OF MASSACHUSETTS.

ELECTRIC-INCANDESCENT-LAMP SOCKET.

SPECIFICATION forming part of Letters Patent No. 703,467, dated July 1, 1902.

Application filed February 28, 1902. Serial No. 96,063. (No model.)

To all whom it may concern:

Be it known that I, GUY H. PROCTOR, a citizen of the United States, residing at Somerville, in the county of Middlesex and State of Massachusetts, have invented a new and useful Improvement in Electric-Incandescent-Lamp Sockets, of which the following is a specification.

My invention consists, essentially, in a combined insulated cap-lining and supporting ears for insulating the cap and receiving the screws for holding the cap to the shell and base.

Referring to the drawings, (twice the size,) Figure 1 is a plan of the combined insulating-lining having attached holding-ears of metal or similar material. Fig. 2 is a second form of the device of Fig. 1 having holding-ears made of the lining material. Fig. 3 is a section of the cap with the lining having the ears of Fig. 1 in place. Fig. 4 is a detail showing the metal ears before being attached to the cap.

Referring to the drawings, A is a cap (sometimes spoken of as a "base") for a socket-shell, (not shown, as its various forms are too well known,) formed with the circumferential bead *a* and the two screw-holes *a'* and the neck portion *a''*.

B is the insulating-lining, of a shape adapted to fit into the concavity of the cap and having several catches *b*, adapted to fit into the circumferential bead *a*, and depending ears *b'*, having the perforated extensions *b''* for reception of the above-mentioned screws, which ears may be formed either, as shown in Fig. 1, of metal or like material, having, as shown, three thin clamping-arms for penetrating the lining and being bent over upon the same and a thickened extension per-

forated at *b''* or, as shown in Fig. 2, whose depending ears *b'* are formed of the insulating material, having threaded eyelets of any proper material set in their extensions constituting perforations *b''*.

I do not claim to be the inventor of the circumferential bead or of holding a lining by means of a bead or of an insulating-lining adapted to fit the cap; but

What I claim is—

1. An insulating cap-lining for the cap of incandescent-lamp sockets, formed to follow the concavity of the cap, and with retaining-catches adapted to fit a bead in the cap, and with depending holding-ears having their thickened extensions perforated to receive the holding-screws which connect the cap, shell, and base.

2. In an electric-incandescent-lamp socket, in combination with the cap A having the circumferential bead *a*, an insulating-lining B, formed to follow the concavity of the cap, and having catches or extensions *b* and holding-ears *b'* perforated at *b''*.

3. In an incandescent-lamp socket, in combination with the ordinary cap having a circumferential bead, an insulating-lining formed to follow the concavity of the cap, and with projections adapted to fit into said circumferential bead, depending metallic ears attached to said lining and perforated at their extremities; substantially as described and shown.

In witness whereof I hereunto subscribe my name this 26th day of February, 1902.

GUY H. PROCTOR.

Witnesses:

FRED C. CHAMBERLIN,
ELSIE D. MCWAIN.
